UNITED STATES PATENT OFFICE.

MAY E. YOUNG, OF NEW MILFORD, CONNECTICUT.

FASTENING DEVICE.

1,204,227.

Specification of Letters Patent.

Patented Nov. 7, 1916.

Application filed May 25, 1915. Serial No. 30,425.

To all whom it may concern:

Be it known that I, MAY E. YOUNG, a citizen of the United States, residing at New Milford, in the county of Litchfield, and State of Connecticut, have invented 5 new and useful Improvements in Fastening Devices, of which the following is a specification.

This invention contemplates the provision 10 of a separable fastener, especially designed for fastening the overlapped edges of garments, such as plackets, gloves, shoes or the like, and is also susceptible to other analogous uses.

15 The invention essentially consists of a socket member constituting the head of the fastener and adapted to receive a relatively separable member of novel construction, which when associated with the socket will 20 be effectively held in interfitting engagement therewith, and capable of being readily and easily separated therefrom without subjecting the fabric or material to which they are secured, to any undue strain.

25 Other objects will appear as the nature of the invention is better understood, the same residing in the construction, combination and arrangement of parts hereinafter more fully described.

30 In the drawing forming part of this application like numerals of reference indicate similar parts in the several views and wherein:—

Figure 1 is a perspective view of one of 35 the members. Fig. 2 is a perspective view of the socket member. Fig. 3 is a sectional view through the fastener with the parts associated. Fig. 4 is a perspective view of a modified form of the invention. Fig. 5 is 40 a similar view of the socket member used in connection therewith. Fig. 6 is a sectional view through these parts operatively associated.

In the preferred embodiment of the invention as disclosed in Figs. 1 to 3 inclusive, the same comprises the members 5 and 6 respectively. The member 5 is constructed from any suitable material preferably metal, and includes a base 7 as shown in this 45 particular instance in the nature of a disk 8 having a plurality of openings 9 for sewing the member to one flap of the garment, although it is to be understood that the base may be of any desired configuration 50 and secured to the garment in any suitable

manner. Rising centrally from the base 7 is a shank 10 of flat material, terminating at its upper edge to provide an outwardly and downwardly extending resilient arm 11, the latter adjacent its lower end being formed 60 with a depression 12 to receive the ridge 13 on the member 6 when the parts are operatively associated as clearly shown in Fig. 3. The lower end of the arm 11 is formed to provide an extension 14 projecting upwardly 65 therefrom and disposed exteriorly of the socket member when the parts are operatively associated, the extension 14 terminating to provide a right angularly disposed manipulating portion 15, for moving the 70 arm 11 to effect a release or separation of the parts when desired, in the manner presently described.

The socket member 6 is constructed from 75 any suitable material and is preferably of circular outline in cross section, being formed at its lower end with diametrically disposed projections 16 constituting the base, the projections being formed with suitable apertures to permit the socket member to be 80 sewed on the overlapping flap of the garment. The socket member should be of a height only sufficient to permit the ridge 13, formed at the lower end and on the inside 85 of the socket member to enter the depression 12 of the member 5, and of a diameter to permit such movement of the arm 11 therein to effect a release or separation of the parts when desired.

In use the socket 6 is forced downwardly 90 over the shank 10 and arm 11 of the member 5 during which time the arm 11 is depressed under tension of the inherent resiliency of the same, until the ridge 13 of the socket member is arranged above the depression 12, whereupon the arm 11 will spring outwardly, the depression 12 receiving the ridge 13 and thereby effectively holding the parts in interfitting engagement with each other. Obviously by reason of this construction the members of the fastener cannot be separated by any pull or strain on the material to which they are secured, it being necessary to depress the arm 11 by means of the manipulating portion 15 to move the depression 12 out of engagement with the ridge 13 of the socket member 6 before the head or socket member 6 can be removed or separated from the member 5.

While structurally different, the principle 110

of operation of the modified form of the invention disclosed in Figs. 4 to 6 inclusive is precisely the same as that hereinabove described in connection with the preferred form. In this form of the invention however, the member 17 comprises a base 18 having suitable apertures to permit the member to be secured to one flap of the garment in any suitable manner. The shank 19 rising centrally from the base is bent at a point in its length and disposed in parallelism with the base, projecting a slight distance beyond the outer edge thereof, the shank terminating in an upwardly and rearwardly projecting resilient arm 20 formed with a depression 21 adjacent the free end 22 thereof, the latter providing a manipulating portion to effect a release of the parts in the manner to be presently described.

20 The member 23 is constructed from a single length of material formed to provide an intermediate tubiform socket 24, the opposite ends of the member projecting beyond the opposite sides of the socket 24 and defining a base 25 adapted to be secured to the overlapping flap of the garment in any suitable manner. The socket 24 is formed with an interiorly disposed circumferential rib 26 adjacent the forward end thereof adapted to engage within the depression 21 of the member 17 when the parts are operatively associated as shown in Fig. 6. In use the socket 24 is slipped laterally over the shank 19 and the arm 20 depressing the latter against its inherent resiliency, until the rib 26 is positioned above the depression 21, at which time the arm 20 will spring outwardly positioning the rib 26 within the depression 21 thereby effectively holding the parts associated. Now when it is desired to separate the members it is only necessary to depress the arm 20 by means of the manipulating portion 22 thereby moving the depression out of engagement with the rib 26, whereupon the socket member may be readily and easily moved out of engagement with the member 17. The device is extremely simple in construction, and may be

made in any size as the occasion may require.

It is believed that from the foregoing description the nature and advantages of the invention will be thoroughly understood without requiring a more extended explanation and therefore the same has been omitted. However I desire to have it understood that I do not limit myself to the precise construction and arrangement of parts herein illustrated, and that various changes in this respect may be resorted to when desired as fall within the scope of the appended claim.

What is claimed is:—

A fastening for securing the overlapping portions of an article together, comprising a socket member having a base adapted to be secured to one portion of the article, an internal circumferential rib formed on said member adjacent its base, a separable member including a base adapted to be secured to the other portion of the article, a substantially inverted V-shaped shank carried by said base and including a relatively fixed branch and a resilient relatively movable branch, the latter being terminally spaced from its base, said movable branch having spaced depressions formed in its length, one for the reception of the lower edge of the socket member in which the latter is crumpled during the operative association of the parts, and the other for the reception of said rib when the parts are associated, and a manipulating portion forming a continuation of said movable branch, said manipulating portion projecting upwardly from beneath said socket and arranged exteriorly thereof and above the material to which said member is attached for the purpose set forth.

In testimony whereof I affix my signature in presence of two witnesses.

MAY E. YOUNG.
